UNITED STATES PATENT OFFICE.

ROBERT H. MCQUIDDY, OF MARSHALL, MISSOURI.

PISTON FOR INTERNAL-COMBUSTION ENGINES.

Application filed March 23, 1927. Serial No. 177,776.

This invention relates to pistons for internal combustion engines and has for an important object thereof the provision of a piston so constructed that it will eliminate piston slap.

A further and more specific object of the invention is the provision of a cylinder construction including a pair of movable wall sections mounted upon chordally disposed faces provided on the piston and means for urging these wall sections apart, so that the effective diameter of the piston is increased, while at the same time a solid unyielding wall face is provided in opposition to the wall of the cylinder.

These and other objects I attain by the construction shown in the accompanying drawings, wherein for the purpose of illustration is shown a preferred embodiment of my invention and wherein:

Figure 1 is a transverse sectional view through a piston constructed in accordance with my invention;

Figure 2 is a section on the line 2—2 of Figure 1;

Figure 3 is a section through a modified piston construction;

Figure 4 is a section on the line 4—4 of Figure 1;

Figure 5 is a rear elevation of the movable wall elements;

Figure 6 is a detail edge elevation of the spring employed.

Referring now more particularly to the drawings, the numeral 10 generally designates the head section and 11 the skirt section of a piston. The skirt section has associated therewith the usual bosses 12 for the reception of the wrist pin (not shown) and the head section 10 is provided with the usual ring grooves 13.

In accordance with my invention, the skirt section 11 is formed with two chordally disposed vertically extending faces 14 which may either be in alignment with one another, as shown in Figure 1, or be disposed at an angle to one another, as in Figure 3. The structure first referred to is preferred where the diameter of the piston is small and that in the latter figure where the diameter of the piston is large and it is desired that the movable wall sections 15 associated with these surfaces be reduced in thickness. The faces of the wall sections 14 are provided with outstanding trans-

versely directed ribs 16 and the adjacent faces of the wall sections 15 are provided with grooves 17 for the reception of these ribs. These wall sections have their outer faces 18 arcuately curved to correspond to the curvature of the wall of the piston and have their adjacent faces recessed adjacent the inner faces thereof to provide a housing 19 for a spring or springs 20, which serve to constantly urge the wall sections apart. As illustrated in Figure 6, these springs are preferably of the single sinuous strip type. Each wall section 14 has a slot 21 formed therein within which operates the shank of a pin or screw 22 engaged with the coacting movable wall element 15 and having at the inner face of the wall section 14 a head 23 holding the movable wall element in proper position against the outer face of the wall section.

It is well known that piston slap is caused by looseness of the piston upon the diameter transverse to the axis of the piston pin bosses and the chordal faces 14 meet upon this diameter at one side of the piston. It will be obvious that when the piston is in place, if there is any space unoccupied by the piston, the springs 20 will force the movable wall sections 15 apart until the piston fills this space, so that the slap will be eliminated. Attention is directed to the fact that since these wall sections in each of the constructions above illustrated are either perpendicular to the diameter or nearly so, they will be substantially immovable to impact in the direction of this diameter and accordingly the piston will be free from self-formed noises, such as are occasioned by wall sections which are movable in the direction of this diameter as have been proposed by previous devices of this character with which I am familiar.

It will be obvious that the construction hereinbefore set forth is capable of a certain range of change and modification and I accordingly do not limit myself to such specific structure except as hereinafter claimed.

I claim:

1. The combination with a piston embodying the usual head and skirt sections and bosses, of chordally extending vertically disposed faces formed upon the piston adjacent to and at opposite sides of a diameter thereof perpendicular to the axis of the

piston pin bosses, a wall section slidable transversely of each face, means urging the wall sections apart and means preventing vertical movement of the wall sections upon the faces.

2. The combination with a piston embodying the usual head and skirt sections and bosses, of chordally extending vertically disposed faces formed upon the piston adjacent to and at opposite sides of a diameter thereof perpendicular to the axis of the piston pin bosses, a wall section slidable transversely of each face, means urging the wall sections apart, each wall face having projecting ribs extending transversely thereof, the rear of each wall section having grooves for the reception of said ribs.

3. The combination with a piston embodying the usual head and skirt sections and bosses, of chordally extending vertically disposed faces formed upon the piston adjacent to and at opposite sides of a diameter thereof perpendicular to the axis of the piston pin bosses, a wall section slidable transversely of each face, means urging the wall sections apart and means preventing vertical movement of the wall sections upon the faces, the wall of the piston having a slot at each face and means slidable within each slot engaging the coacting wall section and having a head engaging the inner face of the piston wall.

4. The combination with a piston embodying the usual head and skirt sections and bosses, of chordally extending vertically disposed faces formed upon the piston adjacent to and at opposite sides of a diameter thereof perpendicular to the axis of the piston pin bosses, a wall section slidable transversely of each face, means preventing vertical movement of the wall sections upon the faces, adjacent faces of the wall sections

having sockets and a spring in said sockets for urging the wall sections apart.

5. The combination with a piston embodying the usual head and skirt sections and bosses, of chordally extending vertically disposed faces formed upon the piston adjacent to and at opposite sides of a diameter thereof perpendicular to the axis of the piston pin bosses, a wall section slidable transversely of each face, means urging the wall sections apart, each wall face having projecting ribs extending transversely thereof, the rear wall section having grooves for the reception of said ribs, adjacent faces of the wall sections having sockets combining to produce a housing and a spring disposed in said housing and urging the wall sections apart.

6. The combination with a piston embodying the usual head and skirt sections and bosses, of chordally extending vertically disposed faces formed upon the piston adjacent to and at opposite sides of a diameter thereof perpendicular to the axis of the piston pin bosses, a wall section slidable transversely of each face, means urging the wall sections apart, each wall face having projecting ribs extending transversely thereof, the rear wall section having grooves for the reception of said ribs, adjacent faces of the wall sections having sockets combining to produce a housing, a spring disposed in said housing and urging the wall sections apart, each of said faces having a transversely extending slot and means slidable within each slot engaging the associated wall section and having a head bearing against the inner face of the piston wall.

In testimony whereof I hereunto affix my signature.

ROBERT H. McQUIDDY.
